UNITED STATES PATENT OFFICE

THEODORE EARLE, OF DENVER, COLORADO

MILLING MACHINE

Application filed April 20, 1928. Serial No. 271,504.

My invention relates to milling machines, more especially to such machines which are adapted to handle conglomerate or other substances including constituents of different hardness and the separation thereof, whereby my process may be carried out.

In some materials such as vanadium deposits or ochre, the valuable constituent is soft and is mechanically or physically but not chemically combined with the gangue.

But in spite of such combination the valuable constituents often adhere to the gangue to such an extent that their economical separation on a commercial scale may present quite a problem.

The object of this invention is to provide a machine for treating and separating such conglomerate substances in which the constituents of the substance may be disassociated by rubbing, and subsequently separated.

My machine intermittently subjects the material to a rubbing action between two relatively moving and intermittently separating rubbing surfaces of different hardness, and thereby rubbing the softer material from association with the harder material and allowing the harder material to temporarily sink into the softer of the two rubbing surfaces to avoid its crushing, splintering or powdering; the intermittent action providing a cooling effect on the material and the surfaces, and also assisting in the disassociation of the constituents of the conglomerate substances treated.

The constituents of the conglomerate substance are next separated, which separation is a part of my process, though it may be performed in some cases hydraulically at the time of the disassociation of the constituents, or in the dry method, it may be performed subsequently to the disassociation stage, except in the case of some special substances noted below.

If performed subsequent to the disassociation stage, the separation may be made by any of the air and gravity methods, or hydraulically, pneumatically, chemically, electrically, magnetically, electro-statically, or in any other well known or proper manner.

But, since the various devices and methods by which the constituents may be separated after their dry disassociation are no part of this invention, they are not shown nor further described in detail herein.

The construction of the device whereby the above process may be put into operation is shown in the drawings, in which;

Figure 1 is a side elevation in partial section of the preferred form of my device, adapted for dry operation.

Figure 2 is a plan view of my machine.

Figure 3 is a side elevation in partial section of a modified form of my device to be used in wet operation combined with hydraulic separation of the constituents of the substance being treated.

Figure 4 is a plan view of the machine shown in Figure 3.

In the device as shown in Figures 1 and 2, the frame 1 supports the rocker shaft brackets 2, which are provided with the roller pins 2', upon which the rollers 3 are mounted.

The frame 1 also supports the pillow blocks 4 in which the shaft 5 is carried. The shaft 5 is to be revolved by any proper driving means.

Upon the rollers 3 is mounted a tank provided with the angle irons 7, which act as tracks contacting with the rollers 3.

The rollers 13' are mounted on pins carried by the brackets 2 and are adapted to prevent rising of the angle irons 7 by contact therewith.

The tank is also provided with the removable rubbing bottom 8, of any proper material as mentioned further, below, properly attached to the tank bottom 8'', and is also provided with the sides 9 to which the angle irons 7 are properly attached, and the removable end plate 10.

The frame 1 as shown is composed of timbers fitted and bolted together, but it may be provided with metal reinforcements, or may be made entirely of metal or of concrete or of any other proper material and construction so long as it properly performs the function required to be performed by the frame as shown.

The rocker shaft brackets 2 carry the rocker shafts 13.

Upon one rocker shaft 13 are properly fitted and keyed the rocker shaft arms 14, which have bifurcated outer ends. And upon all of the rocker shafts are properly fitted and keyed the rocker shaft bellcranks 15, provided with the short double arms 16.

The ends of the bellcranks 15 are joined by a built up tie rod composed of the slotted clevis 17, the slotted clevis 17', the slotted double clevis 18, and the rods 19, whereby all the bellcranks are made to move in unison, and all the rocker shafts are therefore made to rock in unison.

The ends of the rods 19 are threaded and thereby provide adjustment of the distance between the outer ends of the bellcranks, the adjustments being locked by the nuts 20.

The bellcranks 15 are attached to the built up tie rod by the pins 21, held in place by the cotter pins 22.

Any other proper adjustable means for connecting the rocker shafts so they will be forced to rock together may be employed so long as the same results are obtained as in the construction shown.

The shaft 5 is provided with the crank pin 23, upon which is mounted the bifurcated lower lifting rod end 24, having a reduced upper portion 25, and an enlarged shoulder 25'.

The portion 25 fits slidably in the bore of the lifting rod upper end 26, which is pivotally mounted on the rocker shaft arm 14, by the pin 27, which pin is held in place by the cotter pins 27'.

The lower face of the lifting rod upper end 26 is provided with the flange 26'.

Between the upper end of the portion 25 of the lower end 24 and the end of the bore in the upper end 26 is the spring 28, adapted to cushion the contact between the two ends of the lifting rod.

To the bottom of the beams 8' are attached the pillow blocks 29 for the wrist pin shaft 30, which is carried by them.

The connecting rod 31 is mounted upon the crank pin 23 and the wrist pin shaft 30, is straddled on the pin 23 by the bifurcated lifting rod lower end 24.

Mounted on the arms 16 by the pins 16' are the pivoted hangers 33. The pins 16' are held in place by the cotter pins 16''.

The stirrups 34 are slidably mounted on the squared arm portion of the hangers 33.

Threaded through the other arm of the hangers 33 are the double diameter threaded adjusting bolts 37, which are locked in place by the large diameter lock nuts 36.

The small diameter portion of the bolts 37 pass through the stirrups 34, the position of the stirrups 34 being locked by the castle nuts 38, which are threaded upon the small diameter portion of the bolts 37.

The squared end of the small diameter portion of the bolts 37 is used in making the adjustment.

The mullers 39 are pivotally suspended from the bolts 37, between the stirrups 34 and the shoulder furnished by the large diameter portion thereof, and their positions with respect to the pins 16' may be altered by adjustment of the large diameter of the bolts 37 and the lock nuts 36.

To the lower face of each muller 39 is attached the muller plate 40, preferably of rubber, though it may be made of any other proper material, or even integral with the muller 39, so long as its hardness is different from that of the tank rubbing bottom 8.

The tank rubbing bottom 8 may also be made of any suitable material provided it has a hardness different from that of the muller plates 40. But, though the tank rubbing bottom 8 and the muller plates 40 may be varied in material as stated, I believe in the majority of cases the rubbing bottom will be made of wood or metal and the muller plates will be made of wood, rubber, fibre or other suitable material.

As shown, the muller plates 40 are attached by a plural dovetail construction to the mullers, but any other suitable means of attachment may be employed provided it gives the same reliable result.

The position and proportions of the parts are such as to bring the center of gravity of the muller plates, mullers, and assembly which is suspended from the pins 16', substantially in line with their point of support. The adjustment provided by the bolts 37 and the nuts 36 and 38, permit movement of the assembly to alter the relative positions of said centers of gravity and the pins 16' so as to change the hanging positions or slope of the lower faces of the muller plates 40.

In addition to this adjustment the various compartments formed by the ribs of the muller may be filled with weights as desired to assist in providing any required change in balance of the muller assembly on its support, or to add various degrees of pressure to the rubbing surfaces.

The grizzly plate 41 is mounted upon the sides 9 of the tank under the feed bin 42, and is of such length as to support the feed flap 43 during the entire stroke of the tank. The flap 43 of rubber or any other suitable material, is attached to the bin 42 and in conjunction with the grizzly plate 41 and the feed gate 44, and the reciprocating movement of the tank, controls the feed of the material to be treated, from the bin 42 to the tank.

The material is fed from the bin 42, moves downward along the tank rubbing bottom 8 under the action of the mullers and its own reciprocation, as will appear below, and is discharged into the bin 45, whence it is removed for the purpose of the separation of

the constituents of the substance, as mentioned above, by conveyors or in any other proper manner. Or the material may if desired be directly discharged upon a conveyor or directly into any proper part or stage of a separation device or process.

In other words when the material is discharged from the lower end of the tank rubbing bottom 8 it has passed through the dis-
10 association stage, and is ready for the sep-
aration stage of my process.

The actual operation of the device in the passage of the material from the bin 42 to the discharge end of the tank is as follows:—

15 When the shaft 5 is revolved as indicated by the arrow, from the position shown in Figure 1, the tank will roll downward upon the rollers 3 to the position indicated by the dotted lines, this movement being due to the connecting rod 31.

During this down stroke the lifting rod lower end 24 will first move upward in the bore of the upper end 26, compressing the spring 28 till the relative movement of the ends 24 and 26 is stopped by the pressure of the shoulder 25' against the flange 26', the impact being cushioned by the intervening rubber cushion 32.

20 The diameter and thickness of the rubber cushion as well as the diameters of the shoulders 25' and the flanges 26' are to be properly proportioned to the requirements of the particular machine upon which they are mounted, and the particular material being treated and the results desired.

Under some conditions the cushion 32 may be eliminated so that the shoulders 25' may contact directly with the flanges 26'.

25 This initial movement of the lifting rod raises the end of the rocker shaft arms 14, which rocks all the rocker shafts due to their interconnection.

The movement of the rocker shafts raises the mullers and they are held suspended by first an increasing and then a decreasing amount till the downward stroke of the tank is practically completed.

30 That is, when the shaft 5 has revolved 180 degrees from the position shown in Figure 1, the entire muller mechanism except the angular position of the lifting rods will be the same as shown.

On the return upward stroke of the tank, 35 the crank pin 23 first moves downward removing the support of the lower ends of the lifting rods and allowing the mullers to rest their weight upon the material on the tank rubbing bottom 8. As the movement of the crank pin 23 continues, the reduced portion 25 of the lifting rod lower end 24 is partially withdrawn and later returned in the bore of the lifting rod upper end 26.

35 Thus the mullers rest upon and rub upon the material on the tank rubbing bottom 8

during practically the entire upward stroke of the tank.

In this action the rubber faces of the mullers rub the soft material from the harder material, reducing it to a finer condition, 70 while allowing the harder material to sink temporarily into the rubber before being crushed, splintered or powdered.

In some materials the softer constituent will, after disassociation be rubbed together 75 into a cohesive mass, thereby giving a separation of the constituents practically at the same time as the disassociation. But with most materials this will not be the case.

At each upward stroke of the tank some 80 of the material is brushed out of the bottom of the tank by the action of the lowermost muller.

And at each downward stroke of the tank fresh material is fed from the bin 42 under 85 the gate 44, off of the feed flap 43, and through the grizzly plate 41 to the tank rubbing bottom 8, where it is ready for the action of the uppermost muller on the succeeding upstroke of the tank.

The intermittent raising of the mullers from the material being treated permits air to circulate under the mullers and cool both the mullers, the rubbing bottom, and also the material being treated.

90 This intermittent separation of the mullers and the material also permits the soft constituents rubbed free on the previous rubbing stroke to fall and the harder constituents to separate from the mullers so that both constituents may assume new positions and permit more effective results by the rubbing of the succeeding stroke.

The intermittent separation of the two rubbing surfaces therefore not only tends to cool 100 the surfaces and the material, but also adds to the efficiency of the rubbing action of the two surfaces upon the material and hastens the disassociation of the constituents.

Under other conditions the sleeves 35 and 110 the bolts and nuts 37 and 38 may be used to alter the hang of the mullers on the pins 16' so that the plates 40 will be at a slight angle with the tank rubbing bottom 8, thus providing a wedge of material under the mullers which wedge is thicker at the uppermost end of each muller.

115 All the mullers may thus be set to have the same angle with the tank rubbing bottom 8, or each succeeding lower muller may have a slightly smaller angle, or any other setting of the mullers may be made as dictated by the materials and the conditions of each case, as well as the results desired.

120 Weighing certain compartments of the mullers may be employed to work with the angle setting of the mullers or to oppose such setting as the case may be.

125 But these are all points that will be well understood by any competent mill man.

The mullers have a universal mounting due to the pins 16' and the hanger bolts 37, so that they may roll and rise and fall in any way required by the bed of material under them.

It will now be seen that my machine permits my process to be put into operation;—the material is subjected to a rubbing action between the relatively moving and intermittently separating rubbing surfaces of the tank bottom 8 and the muller plates 40, which are of different hardness; the rubbing action disassociates the softer constituent from the harder and the softer rubbing surfaces permit the harder material to temporarily sink therein to avoid being crushed, splintered or powdered; the intermittent action provides a cooling effect on both tank bottom, muller plates, and the material being treated, and by permitting the constituents to assume new positions during the movement of the tank when the mullers are raised, assists in the disassociation of the constituents.

The next stage in my process, that of separation of the disassociated constituents, may be performed either wet or dry, and if the machine shown in Figures 1 and 2 is employed, the separation stage is entirely distinct from the disassociation stage, except with some few special substances noted above in which the softer constituents form a cohesive mass under the action of the mullers.

But, if the disassociation stage is performed under water, which is possible, and even desirable under some conditions, the separation stage may be performed in the same machine directly subsequent to the disassociation stage, so that the disassociation and separation may both be taking place at the same time, some portions of the material being in the disassociation stage while preceding portions are in the separation stage.

The modified form of my machine in which the disassociation and the separation stages are combined is shown in Figures 3 and 4.

The pulp is fed to the tank 1 through the launder 46 or in any other approved manner, falling into one of the mullers which is provided with distribution outlet holes 6. The removable tail plate 47, provided with the overflow edge 48, is attached to the sides 9 and the tank bottom 8'', providing a liquid tight vat at the lower end of the tank.

The liquid portions of the pulp overflow at the overflow edge 48.

The agitation of the pulp in the vat, due to the reciprocation of the tank and to the rise and fall of the mullers, acts to put the softer and finer constituents of the material being treated in suspension whereby they may overflow with the liquid at the overflow edge 48. In this form of my machine the bin 42 and the end plate 10 are dispensed with.

Also, the direction of rotation of the shaft

5 is reversed, as indicated by the arrow in Figure 3.

Thus, on the down stroke of the crank pin 23 from the position shown in Figure 3, the mullers will be allowed to rest upon the tank rubbing bottom 8, and on the upstroke of the tank the mullers will be lifted.

The rubbing action of the two rubbing surfaces upon the material being treated will be the same, except the relative movement of the rubbing surfaces and their intermittent separation will be such as to move the material upward along the tank rubbing bottom 8 on each downward stroke of the tank.

The upper-most muller 49 has its flat rubbing surface removed to the upper edges of the cross ribs where it acts as a support for the ribs, leaving the lower edges of the ribs alone to contact with the tank rubbing bottom 8.

This causes the upper-most muller to act as a rake to prevent the material on the tank rubbing bottom 8 from moving downward on the downward stroke of the tank. This results in the material being finally discharged at the discharge lip 50, where it may be disposed of in any proper manner.

The upper-most muller 49 may be made of rubber or any other proper material depending upon the material being treated and the conditions of each case.

In this form of the device, therefore, the disassociation stage takes place by rubbing between the two rubbing surfaces under liquid, and the separation stage takes place directly after the disassociation of any portion of the material by suspension of the softer and finer constituents and their overflow at the overflow edge 48, while the coarser and harder material travels upward in successive steps due to the strokes of the tank, moving upward along the tank rubbing bottom 8 to the discharge lip 50.

It will be observed that however the disassociation stage is carried out, it is performed by rubbing the material between two relatively moving rubbing surfaces of different hardness, which surfaces separate intermittently. In the dry disassociation, the separation of the rubbing surfaces allows an inrush of air between the two surfaces, and in the wet disassociation the separation of the rubbing surfaces allows an inrush of liquid and pulp between them. In either case the rubbing surfaces and the material are cooled, and a rearrangement of the particles of the material is allowed to take place so that the next rubbing stroke may be upon newly positioned particles and for that reason effective.

I am aware, of course, of variations in both my process and my machines for the operation of my process and which any competent mill man would perceive, and all of which are within the scope of my invention. So, I do

not wish to limit my protection narrowly to the exact description and illustration contained herein, but what I claim as new, and desire to protect by Letters Patent, is as follows:—

1. In a device for the disassociation of the separable constituents of a substance, support means, a rubbing surface mounted to reciprocate thereon, a second rubbing surface adapted to rest upon the first rubbing surface, lifting means mounted on said support means and connected to the second rubbing surface to normally hold it from reciprocation with the first surface, means connected to the first surface and adapted to reciprocate same upon an outward and a return stroke, and means connected to said lifting means and adapted to operate same to lift the second rubbing surface completely from the first rubbing surface during one of said strokes.

2. In a device for the disassociation of the separable constituents of a substance, support means, a rubbing surface mounted to reciprocate thereon, a second rubbing surface of different hardness from the first rubbing surface and adapted to rest thereon, lifting means mounted on said support means and connected to the second rubbing surface to normally hold it from reciprocation with the first surface, means connected to the first surface and adapted to reciprocate same upon an outward and a return stroke, and means connected to the said lifting means and adapted to operate same to lift the entire second surface completely free from the first surface during one of said strokes.

3. In a device for the disassociation of the separable constituents of a substance, support means, a sloping rubbing surface mounted to reciprocate thereon, a second rubbing surface adapted to rest upon the first rubbing surface, lifting means mounted on said support means and connected to the second rubbing surface to normally hold it from reciprocation with the first surface, means connected to the first rubbing surface and adapted to reciprocate same upon an outward and a return stroke, and means connected to said lifting means and adapted to operate same to lift the entire second surface from the first surface during one of said strokes.

4. In a device for the disassociation of the separable constituents of a substance, support means, a sloping surface mounted to reciprocate thereon, a second rubbing surface of different hardness from the first surface and adapted to rest thereon, one of said surfaces being softer than the hardest of said constituents, lifting means mounted on said support means and connected to the second rubbing surface to normally hold it from reciprocation with the first surface, means connected to the first rubbing surface and adapted to reciprocate same upon an out-

ward and a return stroke substantially parallel with its slope, and means connected to said lifting means and adapted to operate same to lift the entire second surface from the first surface during one of said strokes.

5. In a milling device, a rubbing surface provided with means for reciprocation upon an outward and a return stroke, a second rubbing surface adapted to rest thereon, lifting means connected to the second rubbing surface to normally hold it from reciprocation with the first surface, and means connected to the lifting means and adapted to operate same to lift the second entire surface during one of the strokes of the first surface.

6. In a milling device a rubbing surface provided with means for reciprocation upon an outward and a return stroke, a second rubbing surface adapted to rest thereon, lifting means connected to the second rubbing surface, and means connected to the lifting means and adapted to operate same to lift the entire second surface during one of said strokes, including two members having pressure surfaces adapted to transmit pressure during one of said strokes and to separate during the other of said strokes.

7. In a milling device, a rubbing surface provided with means for reciprocation upon an outward and a return stroke, a second rubbing surface adapted to rest thereon, lifting means connected to the second rubbing surface, and means connected to the lifting means and adapted to operate same to lift the second surface during one of said strokes including two members having pressure surfaces and resilient means intervening therebetween and adapted to transmit pressure through said resilient means during one of said strokes and to separate from each other during the other stroke.

8. In a milling device, a rubbing surface provided with means for reciprocation upon an outward and a return stroke, a second rubbing surface adapted to normally rest thereon, lifting means connected to the second rubbing surface, and means connected to the lifting means and adapted to operate same to lift the second surface from contact with the first surface during one of said strokes, including two members and resilient, pressure-transmitting means to transmit pressure between said two members whereby the first surface will be lifted during one of said strokes.

In testimony wherof I affix my signature.
THEODORE EARLE.
